UNITED STATES PATENT OFFICE

129,288

DESIGN FOR A HAND REFLECTOR SIGNAL

Florence Vera Lake, Whitestone, N. Y.

Application March 15, 1941, Serial No. 99,637

Term of patent 7 years

To all whom it may concern:

Be it known that I, Florence Vera Lake, a citizen of the United States of America, residing at Whitestone, in the county of Queens and State of New York, have invented a new, original, and ornamental Design for a Hand Reflector Signal, of which the following is a specification, reference being had to the accompanying drawing, forming part thereof, and in which:

Figure 1 is a front elevational view of a hand reflector signal, showing my new design,

Figure 2 is a side view thereof, and

Figure 3 is a rear elevational view of the same.

The essential features of the new design reside in the spherically shaped back and in the particular surface ornamentation applied around the periphery of the hand reflector signal, as shown in Figure 2.

I claim:

The ornamental design for a hand reflector signal, substantially as shown and described.

FLORENCE VERA LAKE.
